FUEL BURNER SYSTEM

Virgil Robins Tate, Milwaukee, Wis., assignor to
 Perflex Corporation, Milwaukee, Wis., a corporation of Wisconsin

Application March 22, 1940, Serial No. 325,383

4 Claims. (Cl. 236—1)

The invention relates generally to fuel burner systems, and more particularly it relates to automatically controlled burner systems of the two-stage type.

In the heating of some types of buildings it is often desirable to employ a heating system wherein the fuel burner is capable of two stages or rates of heat supply, so that when the room temperature is considerably below the desired value the burner will operate at a relatively high flame or intensity, and when the room temperature is relatively close to the desired value, the burner will operate at a lower intensity. Thus the high level flame is used to raise the room temperature at a rapid rate until the room temperature reaches a level relatively close to the desired value and thereafter the low level flame serves to raise the room temperature at a lower rate until the desired room temperature is attained.

Since the provision of such a two-stage burner operation, in both gas and oil burning systems, involves the selective operation of a low stage fuel valve and a high stage fuel valve, the provision of an automatic control therefor has heretofore been quite difficult and costly. The difficulties involved in producing prior automatic controls for such a two-stage system have been caused principally by the fact that the most desirable fuel valves are of the solenoid-actuated type or the type which is actuated by electrically heated thermostatic means, and to actuate two such valves at different temperatures a relatively complicated room thermostat, having a snap action at each control temperature, has been required. Such snap action has been required at each control temperature because of the relatively heavy current drawn by the actuator of each valve.

The primary object of the present invention is to enable such a two-stage burner to be controlled through the use of a relatively simple and inexpensive room thermostat.

A further object is to provide a new and improved automatically controlled two-stage fuel burner system.

Other objects and advantages reside in certain novel features of construction, circuit arrangement, and operation of the various parts and arrangements which will hereinafter be more fully described in the specification and particularly pointed out in the appended claims.

In the drawing:

Fig. 1 is a schematic view showing a two-stage oil burner system embodying the invention.

Fig. 2 is a similar view illustrating the inven-

tion as embodied in a two-stage gas fired heating system.

While I have illustrated in the drawing and will hereinafter describe in detail two embodiments of the invention, in both of which the high flame operation is attained by simultaneous opening of the two parallel fuel feed lines, and low flame operation is attained by opening one of these fuel feed lines and closure of the other line, it is to be understood that this disclosure is made merely for illustrative purposes and that various changes may be made in the piping and valve arrangement and operation, and in the circuit arrangements, without departing from the spirit and scope of the invention as defined in the appended claims.

While the present invention is applicable to various types of heating systems and to either oil or gas fired burners, it is herein disclosed in Fig. 1 as embodied in an oil burning, warm air heating system having a two-stage oil burner of the pot type, indicated diagrammatically by the reference numeral 10. The fuel oil from a source such as a main supply pipe 11 flows through a by-pass 12 to the burner to provide fuel for a constant pilot flame, and under the control of a room thermostat 13 and a pair of selectively actuatable valves 14 and 15 governed by the thermostat, fuel oil is supplied to the burner at a relatively high rate when the room temperature is substantially below the desired level, and at a lower rate when the room temperature approaches the desired level; and when the desired temperature is attained in the room, the flow of fuel to the burner is stopped with the exception of the pilot fuel which continues to flow through the pilot by-pass 12.

Different arrangements of the valves 14 and 15 are, of course, possible for attaining selectively the desired high rate flow, low rate flow or shut-off of the main fuel supply to the burner, but as herein shown each of the valves 14 and 15 is used in cooperation with an adjustable metering means, and such metering means serves to modify and simplify the piping and valve arrangement. Thus the main fuel pipe 11 has the valve 15 positioned therein, and beyond the valve 15 a branch pipe 16 is connected to the pipe 11. Beyond the branch 16, the pipe 11 is extended to the burner 10 as a branch 17, parallel in a functional sense to the pipe 16, which also leads to the burner 10. With this arrangement the high rate of fuel supply is obtained by opening both of the valves 14 and 15, and the flow of fuel through the pipes 16 and 17 is controlled or regu-

lated by metering valves 16' and 17' located in the branches 16 and 17 respectively. A similar metering valve 12' is also used in the pilot fuel by-pass 12. When with this particular valve arrangement the low rate of fuel feed is desired, the valve 14 is closed while the valve 15 is maintained open; and to shut off the main flow of fuel, both of the valves 14 and 15 are closed, although it will be noted, of course, that closure of the valve 15 would serve to shut off the main fuel flow.

To circulate the heating medium, such as the air heated by the burner 10, the system herein shown has a circulating fan driven by a two-speed motor 19. The fan motor 19 has its low speed winding constantly connected by wires 20 and 21 across the line voltage wires 22 and 23, while its high speed terminal is connected to the wire 23 by wires 24 and 25 and a switch 26 which is adapted to be closed during high flame operation of the burner 10.

In the embodiment illustrated in Fig. 1 of the drawing, the valve 14 is normally closed, and is opened by an electrically energized actuator 27 which is in this embodiment illustrated as an electrically heated thermostatic means; while the valve 15 is normally open, and is closed by a similar electrically energized thermostatic actuator 28. The actuators 27 and 28 have similar thermostatic elements 27' and 28' respectively, each of these thermostatic elements being herein shown as a bimetallic element, and these thermostatic elements 27' and 28' are operatively connected to the valve members of their respective valves 14 and 15. The thermostatic elements 27' and 28' have electric heaters 27" and 28" respectively, and these heaters are adapted to be energized under the control of the room thermostat 13 from a power source such as the secondary 29 of a transformer 30, the primary 31 of which is connected across the line voltage leads 22 and 23.

Electrical actuating devices adapted to open the valves 14 and 15, such as the electrically heated thermostatic actuators 27 and 28, normally require a current flow which necessitates the use of snap action contacts in making and breaking the energizing circuits thereof, and it has been found that where two snap action contacts or switches are embodied in a single room thermostat, it is difficult and costly to establish an accurate or relatively narrow differential in the thermostat. To overcome this difficulty the present invention provides a control circuit for the two electrical actuators 27 and 28 whereby a room thermostat having but a single snap acting switch may be employed. Thus the thermostat 13 has its thermostatic element 35, which is herein shown as a bimetal member, adapted, as it cools, to engage a cold contact 36 with a snap action induced by means such as a permanent magnet 37, the bimetal acting, of course, as an armature. As the thermostatic element 35 increases in temperature, it snaps away from the contact 36 to a central or mid-position as shown in Fig. 1, and, upon continued temperature increase, engages a stationary hot contact 38. Thus the thermostatic element 35 cooperates with the contacts 36 and 38 to provide two switches, one of which has a snap action, and intermediate these two switch closing positions the thermostatic element has a dead-center position in which both switches are open.

The snap acting switch of the thermostat 13 is herein shown as controlling the actuator 27 by

5 being included in circuit with the transformer secondary 29 and the heater 27" of the actuator 27. This circuit includes wires 40 and 41 extending in series from one end of the secondary 29, an auxiliary heater 42, and a wire 43 to the fixed end of the bimetallic element 35. From the contact 36 wires 44 and 45 extend in series to one end of the heater 27", while wires 46, 47 and 48 extend in series from the other end of the heater 27" to the other end of the secondary 29.

To control the other or low flame valve 15, the present invention provides a control circuit governed by the slow acting switch 35-38 of the room thermostat 13 in such a manner as to require but a relatively small current flow between these slow acting contacts 35-38. To this end an energizing circuit is provided for the heater 28" of the actuator 28 which is controlled by a thermally actuated switch 50, and the thermally actuated switch 50 is in turn governed by the thermostat contacts 35-38. The energizing circuit to the heater 28" comprises a wire 51 connected at one end to the juncture of the wires 40 and 41 and at its other end to a stationary contact 52 of the switch 50. The movable contact of the switch 50 is formed by a bimetallic element 53 which is connected by a wire 54 to one end of the heater 28", and the other end of the heater 28" is connected by wires 55 and 56 in series to the juncture of the wires 46 and 47.

30 Where the valve 15 is of the reverse acting or normally open type, the circuit through the switch 50 is normally open, which is to say, the thermostatic or bimetal element 53 is mounted so that when the element 53 is cold it is separated from the contact 52. With this construction the bimetal element is arranged when heated, as by means of an electric heater 57, to move into engagement with the contact 52, and in this movement a snap action is obtained by means such as a permanent magnet 58 which acts on the bimetal element 53 as it approaches the stationary contact 52. A similar snap action takes place, of course, in the opening of the switch 50. The heater 57 has an energizing circuit comprising a wire 59 from the thermostat contact 38 to one end of the heater 57, and a wire 60 from the other end of the heater 57 to the juncture of the wires 55 and 56.

50 Thus when the operation of the burner has caused a room to reach a sufficiently high temperature, the closure of the thermostat contacts 35-38 serves to energize the heater 57, so that the bimetallic element 53 is heated and switch 50 closed with a snap action. The low flame valve 15 is thereby actuated from its normally open position to its closed position, so that the main fuel feed is stopped at what might be termed a pilot level due to the continued flow of a pilot fuel supply through the by-pass 12. As the room 55 cools the bimetallic element 53 of the room thermostat moves away from the contact 38 so as to break the circuit to the heater 57. The bimetallic element 53 of the thermal switch 50 then starts to cool, and when it has stored sufficient power to overcome the attraction of the magnet 58, the switch 50 snaps to its normal open position, thereby to de-energize the heater 28" of the actuator 28 and allow the valve 15 to return to its normally open position. Fuel is then allowed to flow through the pipe 11 to the burner 10 at such a rate as to produce low flame operation of the burner. Ordinarily the low flame operation has a heat producing action which is 60 about one-fourth the heat producing action of

the high flame operation of the burner. If the room temperature continues to fall despite the heat produced by the low flame operation of the burner, the bimetallic element 35 of the thermostat 13 continues to move to the left, and upon a sufficient drop in temperature, is engaged with the contact 36 with a snap action. The circuit to the heater of the actuator 27 is thereby completed, and the high flame fuel valve 14 is opened. The burner then operates at its high flame level so as to supply heat to the room at a comparatively high rate. To prevent "over-shooting" of the room temperature the auxiliary heater 42 is preferably employed to apply added or supplemental heat to the thermostatic element 35 during periods of high flame operation. This auxiliary heater 42 operates in a known manner to compensate for time lag or sluggishness in the heating system. When the thermostat 13 opens the contacts 35-36, the circuit to the heater of the actuator 27 is broken, so that the fuel valve 14 is closed and the burner is returned to its low flame operation.

During the low flame operation of the burner, as well as during the "off" periods of the main burner, the heating medium, such as the warm air, is circulated continuously by the warm air fan, since the motor of the warm air fan is continuously connected across the line voltage leads through the low speed winding of the fan motor 19. During periods of high level operation of the burner 10, the high speed winding of the fan motor 19 is energized through the closure of the switch 26. To effect such closure the switch 26 is in the present instance constructed in the form of a warp switch having a bimetal element 60 which in its normal or cold position is separated from the stationary contact 61 of the switch. To close the switch 26, a heater 62 is provided having one end connected by wire 63 to the juncture of the wires 47 and 48, while the other end of the heater is connected by a wire 64 to the juncture of the wires 44 and 45. Thus when the thermostat contacts 35-36 are closed so as to produce high flame operation of the burner, the heater 62 is energized so as to cause closure of the warp switch 26. Hence the warm air fan starts to operate at its high speed soon after the burner 10 starts to operate at its high flame level. Such high speed operation of the fan continues for a short time after the opening of the thermostat switch 35-36.

When the operation of the heating system is to be discontinued for the season, a main valve 63 in the fuel line 11 is closed, and a line switch 64 in the line voltage lead 22 is opened.

In Fig. 2 of the drawing the invention is embodied in a warm air heating system having a gas fired burner 10, the fuel supply connections of which are substantially the same as those shown in the oil burning system of Fig. 1. In this system, however, the main fuel line 11 has two parallel branches 16a and 17a in which valves 14a and 15a are mounted. The branch pipes 16a and 17a have similar metering valves 16' and 17'. The fuel lines 16a and 17a terminate in individual burner elements 16b and 17b which are herein shown diagrammatically, one above the other, it being understood that this showing is merely illustrative and would be different in practice. In the embodiment of Fig. 2, however, the low flame valve 15a is of also the direct acting type, in that it is normally closed, as indicated by the arrow beside the valve stem, and is opened when its actuator 28a is energized. The actu-

ators 27a and 28a of both of the valves are of the solenoid type, having actuating coils 27b and 28b respectively. In the embodiment of Fig. 2 all of the circuit connections are the same with the exception of the thermal switch 50' which has its bimetal element 53' mounted so as to be normally closed when the element 53' is cold, and the switch 50' is opened by the heating action of its heater 51'. The disposal of the magnet 58' is of course such as to bias the switch member 53' to its switch closing position.

When a relatively high temperature in the room causes the thermostatic element 35 of the room thermostat 13 to close its contacts 35-38, the heater 57' is energized, thereby to cause heating of the bimetal element 53' and consequent opening of the thermal switch 50' with a snap action. Opening of the switch 50' de-energizes the coil 28b of the actuator 28a of the valve 15a so that the valve 15a closes. This results in shutting off all of the fuel to the burner 10' with the exception of the pilot fuel which continues to flow through pilot by-pass 12a and pilot metering valve 12' to a pair of conventional gas pilot burners. When a reduction in room temperature causes opening of the contacts 35-38 of the room thermostat, the warp switch 50' is allowed to cool and thereby closes the circuit to the coil 28b of the solenoid actuator 28a. This opens the valve 15a so as to produce low flame operation of the main burner, which low flame operation continues so long as the thermostatic element 35 remains in its switch opening relation to contact 38. If the thermostat 13 continues to cool, it causes closure of the thermostat contacts 35-36 with a snap action, thereby to open the high flame valve 14a and cause high flame operation of the burner 10'. Soon after the opening of the valve 14a the high speed fan switch 26 is closed due to the action of its heater 62. When the room thermostat has been heated sufficiently to open contacts 35-36, the high flame fuel valve 14a is allowed to close, and the high speed fan switch opens soon thereafter. Operation of the burner then continues at its low flame level until heating of the room causes closure of the contacts 35-38 of the room thermostat.

From the foregoing it will be apparent that the present invention provides a new and improved two-stage fuel burning system wherein a comparatively simple room thermostat may be employed to govern the operation of the two electrical actuators which are required for controlling the fuel supply. It will be apparent that with the present system the control thermostat has but a single snap action, so that the problem of providing an accurate differential in the thermostat is simplified.

What is claimed is:

1. In a two stage control system for fluid fuel burning means, the combination of, fuel supply means for said fuel burning means including supply piping having a single portion and a branched portion, a first fuel valve for controlling the flow of fuel through said single portion, a second fuel valve for controlling the flow of fuel through one of the branched portions, a first electrically operated device for controlling said first valve and arranged to open said first valve when energized and to close the same when de-energized, a second electrically operated device for controlling the second valve, a three position thermostatic switching mechanism located so as to respond to the demand for heat from said fuel burning means, said thermostatic switching

mechanism assuming a first position when the demand for heat is satisfied, a second position when the demand for heat is light, and a third position when the demand for heat is heavy, electrical connections controlled by said thermostatic switching mechanism for controlling said electrically operated devices, said electrical connections being arranged to cause closing of both fuel valves when the thermostatic switching mechanism is in its first position, to cause opening of said first fuel valve when the thermostatic switching mechanism is in its second position, and to cause opening of the second fuel valve when the thermostatic switching mechanism is in its third position, an electric heater associated with said thermostatic switching mechanism for applying false heat thereto, and means including said electrical connections for energizing said heater when the thermostatic switching mechanism is in its third position while substantially deenergizing said heater when the thermostatic switching mechanism is in its second position.

2. In a two stage control system for fluid fuel burning means, the combination of, first and second normally closed fuel valves for controlling the supply of fuel to the fuel burning means, opening of the first valve providing a low rate of fuel supply and opening of the second valve providing a high rate fuel supply, first electric motor means for operating said first valve, second electric motor means adapted when energized to open said second valve, a three position thermostatic switching mechanism responsive to the demand for heat, said switching mechanism comprising first and second switches, the first switch being closed when the temperature to which the switching mechanism responds is above a predetermined value, the second switch being closed when the temperature is below a predetermined value, and both switches being open when the temperature is between said predetermined values, snap action means for causing the second switch of said switching mechanism to open and close with snap action, said first switch being arranged to open and close without snap action, an electric heater associated with said thermostatic switching mechanism, means providing an electric circuit including said second switch for energizing said second electric motor means and said electric heater when the second switch is closed, a slow acting relay for controlling said first motor means, and means providing an electric circuit including said first switch for controlling said relay.

3. In a two stage control system for heating means, the combination of, control means for controlling the supply of heating medium to the heating means, said control means being effective selectively to cause supply of heating medium at a high rate, at a low rate, or to substantially discontinue the supply of heating medium, a three position thermostatic switching mechanism located so as to respond to the demand for heat, said thermostatic switching mechanism assuming a first position when the demand for heat is satisfied, a second position when the demand for heat is light, and a third position when the demand for

heat is heavy, snap action means for causing said switching mechanism to move with snap action between its second and third positions, said switching mechanism being arranged to move slowly between its first and second positions, a slow acting relay moving from one position to another a period of time following movement of the switching mechanism between its first and second positions, electric heating means associated with 10 said thermostatic switching mechanism for adding false heat thereto, means including electrical connections between said switching mechanism said slow acting relay and said control means for causing a supply of heating medium at a high 15 rate when the switching mechanism is in its third position, at a low rate when said mechanism is in its second position, and for substantially discontinuing said supply when the switching mechanism is in its first position, and means including 20 said electrical connections for energizing said electric heating means when the switching mechanism is in its third position and for substantially deenergizing the same when the switching mechanism is in its second position.

4. In a two stage control system for a temperature changer, the combination of, control means for controlling the effectiveness of the temperature changer, said control means being effective selectively to cause the temperature changer to 30 operate at a high rate, at a lower rate or to be substantially inoperative, a three position thermostatic switching mechanism located so as to respond to the demand for temperature changing, said thermostatic switching mechanism assuming a first position when the demand for temperature change is satisfied, a second position when said demand is light, and a third position when said demand is heavy, snap action means for causing said switching mechanism to move with snap action between its second and one of said positions, said switching mechanism being arranged to move slowly between said second and the other of its positions, a slow acting relay controlled by said thermostat switching mechanism and moving from one position to another a period of time following movement of the switching mechanism between its second and said other of its positions, electric heating means associated with the thermostatic switching mechanism for adding false heat thereto, means for energizing and deenergizing said electric heating means in a manner tending to cause cycling of the thermostatic switching mechanism between its second and said one position whereby the electric heating means supplies power for operating the thermostatic switching mechanism against said snap action means, and means including electrical connections between said thermostatic switching mechanism, said slow acting relay and said control means for causing the temperature changer to operate at said high rate when the switching mechanism is in its third position, at said lower rate when said mechanism is in its second position, and for rendering the temperature changer substantially inoperative when the switching mechanism is in its first position.

V. ROBINS TATE.
